Primary Examiner — S. Bryan Reinholdt, Jr.*Assistant Examiner* — James T Tyree(74) *Attorney, Agent, or Firm* — Troutman Pepper Hamilton Sanders LLP; John A. Morrissey; Aaron E. Johnston(57) **CLAIM**

The ornamental design for an inner core of a transparent wheel, as shown and described.

DESCRIPTION

FIG. 1 is a front right perspective view of an inner core of a transparent wheel;

FIG. 2 is a front view thereof, which is identical to the back view;

FIG. 3 is a left side view thereof, which is identical to the right side view, the top view, and the bottom view;

FIG. 4 is a first sectional view thereof along dashed line 4 from FIG. 2; and,

FIG. 5 is a second sectional view thereof along dashed line 5 from FIG. 2.

The broken, dashed lines shown in the various figures depict portions of the inner core for transparent wheel that do not form any part of the claimed design.
